UNITED STATES PATENT OFFICE.

FELIX E. LIETZ AND JOHN REIMERS, OF BUFFALO, NEW YORK.

VALVE.

1,149,845.

Specification of Letters Patent. Patented Aug. 10, 1915.

Application filed March 16, 1914. Serial No. 824,842.

To all whom it may concern:

Be it known that we, FELIX E. LIETZ and JOHN REIMERS, citizens of the United States, residing at Buffalo, in the county of Erie 5 and State of New York, have invented certain new and useful Improvements in Valves, of which the following is a specification.

Our invention relates to improvements in 10 valves, and more particularly to automatic safety gas valves; its primary object being the provision of a valve of this type which will automatically shut-off the supply of gas when the pressure becomes dangerously 15 low and may cause the gas burners to become extinguished, which under ordinary conditions would permit the gas to again flow to the burners when the pressure is increased, thereby causing the escape of gas, which 20 would cause asphyxiation of the occupants of the building if such an occurrence took place during the night.

A further object of our invention is the 25 provision of a simple and inexpensive valve for this purpose which can be easily regulated and which will effectively shut-off the supply of gas, either when the pressure is exceedingly low or when it ceases to entirely flow, as may be desired; this being 30 controlled entirely by the weight of a single part of our invention.

With these and other objects in view, our 35 invention consists in the novel features of construction and in the arrangement and combination of parts to be hereinafter described and more particularly pointed out in the subjoined claims.

Our invention is illustrated in the accompanying drawings in which,—

40 Figure 1 is a central vertical section of a valve with a gas inlet-pipe and a gas outlet-pipe applied thereto. Fig. 2 is a horizontal section taken on line $y-y$, Fig. 1. Fig. 3 is a horizontal section taken on line $z-z$, 45 Fig. 1.

In carrying out our invention we provide 50 a casing 4 which is preferably of cylindrical formation in cross-section and has a rounded lower end 5 and an open upper end. This casing is constructed in two parts 7, 8, having outstanding flanges 9, 10, respectively, through which are passed securing screws 11. The joint thus formed between the two parts of the casing may be provided with

any suitable packing means, or any other 55 form of connection between these parts may be resorted to, as we believe various forms of connections to be suitable for the purpose intended, it being merely necessary that the joint be gas tight. 60

In the lower part 8 of the casing, a dia- 65 phragm 12 is arranged which has a central opening or passage 13 flared at its upper portion to provide a valve seat 14, and rising from the rounded wall at the bottom of the casing is a guide boss 15, for a purpose to presently appear. The lower part 8 of the casing has a lateral tube 16 which is externally threaded to receive a socket 17 in which a gas inlet-pipe 18 is threaded, and 70 in the tube 16, which may be termed an "inlet-tube," a strainer thimble 19 is inserted which is preferably formed of fine wire gauze and prevents the admission into the casing of any matter likely to become seated 75 against the valve seat 14 and prevent the proper seating of the valve, to be hereinafter described.

Formed in the rounded lower end of the 80 casing part 8 is a drain opening 20 in which is threaded a cock 21 normally closed, but which may be opened to drain from the casing any matter that may accumulate therein, or to permit the thorough cleansing of the 85 casing by introduction through its open top of water or other liquid.

The upper part 7 of the casing has two 90 cross bars 22, 23 formed therein, the lower of these having a guide opening 24 therein whose axis is coincident with that of the valve seat, and in this guide opening is situated for guiding movement the upper end portion of a valve stem 25 which has its lower end guided in the guide boss 15. This 95 valve stem has formed thereon or secured thereto, as may be found most desirable, a downwardly tapering valve 26 adapted for seating engagement with the valve seat 14 in the diaphragm 12. Said valve and valve stem are preferably made of aluminum or 100 other suitable light material so that the pressure of the gas entering the inlet tube 16 will raise the same and retain it in elevated position to permit the gas to pass through the opening or passage 13 and enter 105 the portion of the casing above the dia- phragm 12, from which it escapes through an outlet tube 27, having connected thereto

an outlet gas-pipe 28 by means of a socket 29. The inlet gas-pipe 18 and the outlet gas-pipe 28 open into the casing at opposite sides of the diaphragm and constitute the main gas supply pipe in which our improved valve may be said to be introduced.

When the gas pressure becomes low, the gas valve 26 and its stem will gravitate and cause the opening or passage 13 in the diaphragm to be closed, the pressure at which said valve closes being determined by the weight of said valve, which may be sufficiently light, if desired, that the pressure at the burner will be insufficient to keep the gas burning. The weight of the valve, however, is preferably such that when the gas pressure becomes sufficiently low that a further slight reduction of the same would cause the gas to become extinguished, the gas valve will close.

When the valve is closed, regardless of the gas pressure it may be constructed for, it is our intention to provide practicable means to retain the same in closed position so that when the pressure again rises the valve cannot open and permit the gas to escape from the burner unlighted. For this purpose we provide a lock dog 30 which is arranged directly over the valve stem 26 and conveniently pivoted to the upper cross bar 22, as at 31. Said lock dog normally rests against the side of the valve stem and when the valve lowers, it swings over the upper end of said stem and prevents the same from rising. In order to prevent this lock dog swinging beyond the valve stem, the latter has an upwardly extending teat or lip 32 which serves as a stop for the dog in its swinging movement, and for this purpose said teat is arranged at one side of the axis of said rod so that the lock-dog may bear against the upper end of said stem while in contact with said teat.

In Fig. 1, the lock dog 30 is shown in dotted lines in locking position and arranged on the casing in the plane of the same is a stuffing box 33 through which is passed a push pin 34 having a handle 35 at its outer end for conveniently manipulating the same and a stop collar 36 at a point within the casing to prevent the complete withdrawal of the pin from said casing. In the position in which the pin is shown, the lock dog has freedom in action so that when the gas pressure reaches the predetermined point at which the valve is to close, said dog will automatically swing into engagement with the upper end of the valve stem and prevent the valve from becoming unseated.

When it is desired to permit the gas valve to become unseated through the action of the gas pressure against the underside thereof, it is simply necessary to force the push pin 34 inwardly to bring the inner end thereof against the lock dog, which action

forces the latter out of engagement with the valve stem, thus permitting the valve and its stem freedom in action.

It is to be noted that the valve 26 is hollowed out and has its lower end open, this being for the purpose of reducing the weight of the same and also enlarging the surface against which the gas exerts its pressure, the inner wall face 37 of the valve being somewhat larger by reason of this than the diameter of the same at its lower end.

Although we have herein stated that the upper end of the valve casing is open, it is clear that to prevent the escape of gas this open end must be closed, and for this purpose the casing is exteriorly threaded for engagement therewith of a flanged collar 38 which serves to retain against the upper edge of the casing a glass cover 39 between which and the said edge a rubber gasket or other packing 40 is interposed. This glass cover we believe to be desirable so that the interior of the valve will be exposed to view and its operation more easily controlled, but it is apparent that while this may be desirable it nevertheless is unnecessary to the proper action of the device and any other cover may be substituted for the glass cover, or a head integral with casing may be employed.

It is to be understood that slight changes in construction may be resorted to without departing from the spirit of our invention or sacrificing any of the advantages thereof.

Having thus described our invention, what we claim is,—

1. A device of the character described, comprising a casing formed of upper and lower connected parts, said lower part having a diaphragm with a gas passage and a gas inlet beneath said diaphragm, said upper part having two cross bars and a gas outlet, a gas valve having a valve stem guided at its lower end in said lower part and its upper end in one of said cross bars, said gas valve being adapted to close said gas passage when the gas pressure reaches a predetermined low point, a lock dog pivotally secured to the other cross bar and adapted to swing against the upper end of said valve stem when the gas valve is closed, and means adapted for engagement with said lock dog to swing the same out of engagement with said valve stem.

2. A device of the character described, comprising a casing having a diaphragm with a gas passage and a gas inlet and gas outlet at opposite sides of said diaphragm, a valve adapted to close said gas passage having a valve stem provided with an upwardly projecting teat at its upper end, said teat being arranged off center and said valve stem being guided within said casing, a lock dog pivotally secured above said valve stem and adapted to swing in contact with the

upper end thereof and against said upwardly projecting teat, and a push pin in the plane of said lock dog extending through the wall of said casing and having a stop 5 collar to prevent withdrawal of said push pin from said casing, said push pin being adapted to swing said lock dog out of engagement with said valve stem.

In testimony whereof we affix our signatures in presence of two witnesses.

FELIX E. LIETZ.
JOHN REIMERS.
